UNITED STATES PATENT OFFICE.

AUTHUR B. FRENZEL, OF DENVER, COLORADO.

WATER-LIFTING APPARATUS.

1,183,863.

Specification of Letters Patent. Patented May 23, 1916.

Application filed February 10, 1914. Serial No. 817,830.

To all whom it may concern:

Be it known that I, ARTHUR B. FRENZEL, a citizen of the United States, residing at Denver, in the county of Denver and State 5 of Colorado, have invented certain new and useful Improvements in Water-Lifting Apparatus, of which the following is a specification.

My invention relates to improvements in 10 water lifting apparatus and its object resides in the provision of an apparatus which is capable of lifting water by the action of a rotary, helical element from a shallow depth in river-bottoms and the like, with 15 the minimum of power in relation to its capacity.

In accordance with my invention I provide a cylindrical, open-ended barrel connected at its upper end to a conduit of inverted truncated cone form, with which it is in axial alinement. The barrel is surrounded by a foraminous casing for the purpose of excluding stones, sand and other solids from its open, lower end, and the entire device thus constructed is adapted to be inserted into an excavation formed in a river bottom or other place having a subterranean water supply. The conduit and the therewith connected barrel are suspended 20 from a structure which in practice rests upon the surface of the ground and which supports the operative parts of the apparatus. These parts include a hollow shaft which is rotatably mounted in the axis of 25 the device, upon a step at the lower end of the casing which surrounds the pump-barrel, and in a bearing which is formed in a yoke which is mounted on the supporting structure.

40 The means for imparting a rotary movement to the shaft include a driven wheel which is secured at the upper end thereof and by means of which it is suspended from the support which to this end, is provided 45 with a bearing, preferably of the anti-friction, cone roller type.

Mounted on the shaft within the barrel is a helical lifting element of gradually increasing pitch which may be formed either 50 of a plurality of screw propellers or of a single or multiple advancing spiral blade.

Means are provided for counteracting the swirling motion imparted to the upwardly impelled column of water and a col-

lar on the shaft prevents its upward displacement by engagement with the supporting structure. 55

In the operation of the apparatus, the barrel and conduit are inserted in an excavation of the river-bottom, which is made of sufficient diameter to permit of surrounding the same with a wall of broken stone or rocks to prevent clogging of the foraminations in the casing which surrounds the pump-barrel. 60

If so desired the excavation may be lined by inserting thereinto a perforated cylinder which can be secured to the supporting structure, in which case the rocks are placed in the space between said casing and the alined conduit and barrel with which it is concentric. 65

The water which enters the pump barrel, practically free from solids, is raised by the rotary motion of the helical element, which 75 is imparted thereto by power applied to the driven wheel at the upper end of the shaft.

The gradually increasing pitch of the lifting element gives to the ascending column of liquid, an upward thrust which greatly 80 increases the lifting power of the apparatus.

The gradually increasing diameter of the conduit in which the water rises to a discharge spout at the upper end thereof, decreases the speed of the water as it rises 85 after leaving the pump-barrel, and thereby renders the movement of the operating parts more effective, and the means provided for counteracting the swirling motion imparted to the water by the action of the lifting element, further aid in imparting a steady 90 flow to the rising column and in eliminating forces retardative to the upward motion of the same.

The suspended mounting of the operative 95 parts of the pump, permits of their being removed for cleaning or repairs without the necessity of disturbing the stationary parts of the apparatus, and without the use of special tools or the employment of skilled 100 labor.

By introducing compressed air, steam or other fluid under pressure, into the upper end of the tubular shaft, the space below and around the barrel may be readily cleared 105 in case the flow of water to the barrel or the movement of the lifting element are obstructed, and in case the pump has become

inoperative by freezing, the introduction of steam into the shaft will be effective to restore it to its working condition.

Having thus described the construction, 5 operation and advantages of my improved water lifting apparatus, I will now proceed to describe the parts of which it is composed, in detail, by reference to the accompanying drawings in the various views of 10 which like parts are similarly designated, and in which;

Figure 1, is a vertical, axial section through the apparatus in its preferred form, Fig. 2, a similar section showing a modification 15 in the construction of the same, Fig. 3, a longitudinal section through the barrel of the apparatus, showing a modified construction of the helical lifting element, rotatably disposed therein, Fig. 4, a section taken along the line 4—4, Fig. 1, and Fig. 5, a transverse 20 section along the line 5—5, Fig. 2.

The reference numeral 2 designates the barrel surrounded by the foraminous casing 3 which at its lower end is closed by a 25 perforated bottom 4.

The conduit 5 which as hereinbefore explained, is made in the form of an inverted, truncated cone, has at its lower end, a flange by which it is attached to flanges formed at 30 the upper ends of the casing and the barrel, for the purpose of their connection and of closing the space between them at their said ends.

The numeral 6 designates the supporting 35 structure which may be of any suitable construction and upon which is mounted the yoke 7 provided with the cone-roller, anti-friction bearing 8.

The tubular shaft 9 rotatably disposed in 40 the axis of the axially aligned conduit and barrel is supported upon a ball-bearing step 10 in the center of the bottom of the casing 3, and the bevel gear-wheel 12 secured at the upper end of the shaft is rotatably supported 45 in the bearing on the yoke.

The gear wheel is in operative engagement 50 with a pinion 13 mounted at the end of a driving shaft 14 which by means of a pulley 15 may be connected with any convenient driving medium.

A collar 16 which is detachably secured to the shaft beneath the yoke, serves to prevent its upward displacement and a screw thread formed internally at the upper end of the 55 shaft as best shown in Fig. 2, may be used for the connection of a tubular conduit through which a fluid is introduced into the shaft for the purposes hereinbefore set forth.

The helical lifting element of my invention 60 consists in its preferred form, as shown in Fig. 1, of a plurality of screw propellers 17 which are mounted on the portion of the shaft within the barrel in alternate order with devices for counteracting the swirling 65 motion they impart to the rising column of

water. These devices consist preferably of rings 18 having radial arms 19 which upon their sides forward with relation to the direction of rotation of the element, have baffles 20 provided by vertically extending ribs. 70

The devices are supported in the barrel upon lugs 21 secured upon its inner surface to receive the ends of their radiating arms while the rings are placed concentrically around the shaft. 75

The screw propellers each of which comprises a hub and a plurality of radiating blades, are with the object hereinbefore explained, made of different pitch which increases progressively from the lowermost screw to that nearest the upper end of the 80 barrel.

In the form shown in Fig. 3, the screw propellers are mounted one upon the other without baffling devices of the construction shown in Fig. 1, and in Fig. 2 the lifting element is provided by a double helical blade 22 of gradually increasing pitch which is mounted on the shaft, inside the barrel, by means of a sleeve 23 around which it is 90 formed. 85

The conduit through which the water lifted by the action of the helical element, rises to the surface of the ground, is preferably made of longitudinally corrugated 95 metal, the corrugations serving to stop any swirling movement in the column of water after it has left the barrel, as well as to strengthen the construction.

The apparatus is as shown in Figs. 1 and 100 2, placed, in practice, in an excavation 24 and surrounded by broken stones or rocks 25.

In the construction shown in Fig. 1, the excavation is lined by means of a perforated 105 casing 26 connected with the supporting structure by means of a flange, to aid in excluding solids from the operating parts of the apparatus, and in both Figs. 1 and 2 the level of the water in the subterranean 110 source is indicated by a line designated by the numeral 27.

Having thus described my invention what I claim and desire to secure by Letters-Patent is:

1. A pump comprising an upright, open-ended barrel, a conduit connected at the upper end thereof, and a lifting element comprising a plurality of screw-propellers which increase in pitch progressively from the 120 lower one to the upper one, mounted in the barrel for rotation about a common, vertical axis.

2. A pump comprising an upright, open-ended barrel, a conduit connected at the upper end thereof, a lifting element comprising a plurality of screw-propellers mounted in the barrel for rotation about its longitudinal axis, and devices for counteracting the swirling motion imparted to the rising liquid. 130

uid by the action of said element, disposed in alternate order with relation to the said propellers, and each including radially extending blades having baffles provided by upwardly extending ribs.

3. In a pump, a stationary element comprising an open-ended barrel, an apertured casing surrounding the same, a conduit connected at the upper end of the barrel and

10 means for suspending the element in a well or other source of water-supply, and an operating element comprising a hollow open-ended shaft which is rotatably mounted on the stationary element, and which extends 15 at its lower end into an aperture of the casing for the ejection of fluid exteriorly of the same, and a lifting element connected with the shaft within the casing.

4. In a pump, a stationary element comprising an upright open-ended cylinder and a surrounding foraminous casing of greater length, which are spaced from each other to provide below and around the barrel, a water-receiving chamber, and which are connected at their upper ends so as to close the space between them, an outwardly flaring conduit extending upwardly from the connected ends of the barrel and the casing, to receive water expelled from the barrel,

30 means for suspending the element in a well or other source of water supply, and an operating element comprising a rotary shaft and fixed thereon, a helical lifting device rotatably disposed within the barrel.

25 5. In a pump, a stationary element comprising an upright open-ended, cylinder, an outwardly flaring conduit connected at the

upper end of said cylinder to receive water expelled therefrom, means for suspending the element inside a well or other source of 40 water supply, and an operating element comprising a rotary shaft and on the same, a helical lifting element of gradually increasing pitch which is rotatably fitted in the cylinder.

45 6. In a pump, a stationary element comprising an upright, open-ended, cylinder, an outwardly flaring conduit connected at the upper end of said cylinder to receive water expelled therefrom and having means for 50 counteracting the swirling motion of the water, means for suspending the element inside a well or other source of water supply, and an operating element comprising a rotary shaft and on the same, a helical lifting 55 element of gradually increasing pitch which is rotatably fitted in the cylinder.

7. In a pump, a stationary element comprising an upright open-ended cylinder, a conduit connected at the upper end of said 60 cylinder to receive water expelled therefrom, means for suspending the element inside a well or other source of water-supply, and an operating element comprising a rotary shaft and on the same, a helical lifting element of 65 gradually increasing pitch which is rotatably fitted in the cylinder.

In testimony whereof I have affixed my signature in presence of two witnesses.

ARTHUR B. FRENZEL.
